United States Patent

Des. 239,109

Patented Mar. 9, 1976

239,109

SERIES RL/RC CIRCUITS EDUCATIONAL BOARD

Douglas C. Covert, Royal Oak, Mich., assignor to
Xerox Corporation, Stamford, Conn.

Filed May 30, 1974, Ser. No. 474,499

Term of patent 14 years

Int. Cl. D19—07

U.S. Cl. D19—62

FIG. 1 is a top right front perspective view of a series RL/RC circuits educational board showing my new design; and

FIG. 2 is a bottom left front perspective view thereof.
The rear of the educational board not shown is plain and unornamented.

I claim:

The ornamental design of a series RL/RC circuits educational board, substantially as shown.
